[57] ABSTRACT

A light, plastic razor except for the metal blade therein comprising a plastic cover, a guard plate, a metal blade between said guard plate and said cover, a guard edge juxtaposed below the blade edge and joined to said guard plate, a handle attached to the bottom surface of the guard plate and rectilinearly extending therefrom along a plane which is essentially perpendicular to the bottom surface, which handle is fragmented into three sequential sections, the first section is a non-flexible, rigid plastic member, the second section, which is directly joined to said first section and the third section, is a non-stretchable flexible, elongated plastic member having a cross-sectional area, determined perpendicular to its length, which is substantially less than the corresponding cross-sectional area of the first and third sections, and the third section is a non-flexible, rigid plastic member extending from the second section.

FIG. 2

PLASTIC SAFETY RAZOR

This invention is directed to a novel safety razor constructed particularly for use on legs and areas of the body containing low hair density, such as arms, under-arms, chest, and the like, as well as the high density areas, such as the beard of a male's face.

In my U.S. Pat. No. 3,571,927, patented Mar. 23, 1971, there is described a safety razor containing a non-stretchable, flexible elongated member connected to one end to the bottom of the guard plate and on the other end to the handle. The handle is laterally extended from the plane of the member. This unique structure has a shaving action which one might call a "floating action," responding immediately to skin projections to give a gentle shave without tilting the head onto the guard edge. However, if the handle were in the same plane as the elongated flexible member, then the head would be deflected upon the guard edge when the head is suddenly deflected by a skin projection.

I have now found a novel shaver construction which possesses a non-stretchable and flexible component associated with the handle and possesses the floating action of my aforementioned patented razor, yet the handle and the flexible member are in the same plane and along a single line extending from the bottom surface of the guard plate. The structure of my new razor is significantly less susceptible to deflection of the razor head upon the guard edge when the head is suddenly deflected by a skin projection.

The safety razor of this invention is distinctive in that it possesses a plastic handle attached to the bottom surface of the guard plate which rectilinearly extends therefrom along a single plane aligned perpendicular to the bottom surface. The handle is fragmented into three sequentially interconnected sections, a first section which is non-flexible and rigid, a second section which is flexible and non-stretchable, and a third section which is non-flexible and rigid. The sequential order of each section of the handle extending from the bottom surface of the guard plate is the first, second and third sections in that order. The cross-sectional area of the second section is substantially less than the corresponding cross-sectional areas of each of the first and third sections.

The handle with its various sections can be constructed of the same or different plastic material and as a single piece or from a plurality of pieces. In the preferred embodiment, the razor handle is made in a single mold from one thermoplastic or thermosetting plastic. The length of the handle is not critical to this invention except that if the handle is made of a single plastic, the second section should be either long enough or thin enough or a combination of both to provide the desired flexibility.

In this invention, the term "non-stretchable" means the inability to stretch at room temperature (about 25°C.) as does an elastic and a U-shaped spring, e.g., as shown in U.S. Pat. Nos. 1,423,414; 1,015,575; 2,053,250 and 2,083,172.

In order to further illustrate the novel safety razor of this invention, reference is made to the drawing.

FIG. 1 is a perspective view of a razor encompassed by this invention.

FIG. 2 is a side view of a razor encompassed by this invention.

FIG. 1 contains two components, shaving head A and handle B. FIG. 2 emphasizes handle B.

The shaver of FIG. 1 consists of cover 1, guard plate 3, blade 2, guards 4, and flat guide edges 5. These elements are explained in my U.S. Pat. No. 3,571,927, and col. 2, lines 50-75 and col. 3, lines 1-62 thereof are incorporated herein by reference to the extent such pertains to elements 1-5 and 10 disclosed therein.

With respect to FIGS. 1 and 2, handle B is attached 10 to the bottom surface of guard plate 3. As shown, it contains three sections 8, 9 and 11, in which section 8 corresponds to the aforedefined first section, section 9 corresponds to the aforedefined second section and section 11 corresponds to the aforedefined third section. In the case of FIG. 1, section 9 is a thin and flat piece while section 9 of FIG. 2 is cylindrical. The cross-sectional area of section 9, determined across a perpendicular to the elongated axis thereof, is typically much smaller than the corresponding cross-sectional areas of 20 section 8 and 11.

The flexibility of handle B is dependent upon the thickness of section 9 at its narrowest dimension. By such thickness, one can control the floating action of the razor.

25 In use, section 8 (corresponding to the first section) separates the shaving head A from flexible section 9. It is desirable that the length of section 8 should not be greater than 1 inch, preferably not greater than three-fourths inch, and greater than one-fourth inch, preferably greater than three-eighths inch. Because of the presence of section 8, non-stretchable and flexible section 9 does not affect the toppling characteristics of shaving head A and thereby minimizes the deflection of head A upon guard edge 4 when the blade hits a skin projection or is used on a heavy or dense hair growth. If section 8 were eliminated and section 9 were directly connected to the bottom surface of guard plate 3, such deflection of the shaving head A would be prevalent.

30 The handle, as with the remainder of the shaver (other than the blade), is made of plastic, preferably one which has a 1 percent tensile modulus of at least 10,000. This means the plastic is not rubbery and is non-stretchable. The plastic is one which can be shaped by such molding processes as compression molding, 35 transfer molding, and injection molding. Illustrative of suitable plastics are thermoplastics such as nylon, polyester, polyethylene, polypropylene, polystyrene, polycarbonate, poly(oxymethylene), ABS block copolymers, polyvinylchloride, and the like, and thermosetting plastics such as phenol formaldehyde resins, resorcinol formaldehyde resins, melamine formaldehyde resins, polyurethane resins, epoxy resins, and the like.

40 Though this invention has been described with respect to a plurality of details, thereof, it should not be limited thereby, nor is intended to be so limited except as recited in the claims.

45 What is claimed is:

1. A light, plastic razor except for the metal blade 50 therein comprising a plastic cover, a guard plate, a metal blade between said guard plate and said cover, a guard edge juxtaposed below the blade edge and joined to said guard plate, a handle attached to the bottom surface of the guard plate and rectilinearly extending 55 therefrom along a plane which is essentially perpendicular to the bottom surface, which handle is fragmented into three sequential sections, the first section is a non-flexible, rigid plastic member directly and non-flexibly

connected to the bottom of the guard plate, the second section, which is directly joined to said first section and the third section, is a non-stretchable flexible, elongated plastic member having a cross-sectional area, determined perpendicular to its length, which is substantially less than the corresponding cross-sectional area of the first and third sections, and the third section is a non-flexible, rigid plastic member extending from the second section.

2. The razor of claim 1 wherein the second section is cylindrical.

3. The razor of claim 1 wherein the second section is a thin flat piece.

5 4. The razor of claim 1 wherein the first section has a length not greater than about 1 inch and not less than one-fourth inch.
